AIR COMPRESSOR

James Y. Taylor, Brownwood, Tex., assignor of
one-sixth to Oran A. Milam, one-sixth to Rob-
ert E. Milam, and one-sixth to Douglas
Coalson, Brownwood, Tex.

Application September 25, 1931, Serial No. 565,087

6 Claims. (Cl. 230—50)

This invention relates to new and useful im-
provements in air compressors.

One object of the invention is to provide an
improved air compressor particularly adapted to
5 be attached to one of the cylinders of an internal
combustion engine, whereby the reciprocation of
the piston in said cylinder may be utilized to oper-
ate the compressor.

A particular object of the invention is to pro-
10 vide an air compressor for attachment to the cyl-
inder of an internal combustion engine and in-
cluding means whereby the intake or suction
stroke, as well as the compression stroke, may be
utilized in the operation of the compressor, with
15 the result that a much higher compression can
be built up than has been heretofore possible.

A further object of the invention is to provide
20 a compressor employing a plurality of pistons
and means for cushioning the pistons at the ends
of their strokes, thus eliminating undue shock
and saving the parts from injury.

Still another object of the invention is to pro-
25 vide a new and novel mounting for the compres-
sor, whereby the usual spark plug may be em-
ployed and the compressed gases thus exploded,
thereby eliminating the injurious results which
would occur if such gases were not ignited, and
also whereby the spark plug may be removed or
30 replaced without interfering with the connection
of the compressor.

A construction designed to carry out the inven-
tion will be hereinafter described together with
other features of the invention.

The invention will be more readily understood
35 from a reading of the following specification and
by reference to the accompanying drawing in
which an example of the invention is shown, and
wherein:

Figure 1 is a vertical sectional view of an air
40 compressor constructed in accordance with the
invention and mounted on the upper end of an
engine cylinder, a portion of which is shown in
section, and

Figure 2 is a partial horizontal cross-sectional
45 view taken on the line 2—2 of Figure 1.

In the drawing the numeral 10 designates a
lower operating or motor cylinder which is sur-
50 mounted by a smaller compressing cylinder 11. It
is obvious that these cylinders may be made in
one piece or they may be made separately and
suitably connected. The interior of the cylinder
10 constitutes an operating chamber A, while the
55 interior of the cylinder 11 constitutes a compress-
ing chamber B.

In carrying out the invention, the chamber A is

connected with the cylinder of the internal com-
bustion engine and for this purpose I have shown
a bracket 12 having an internally threaded flange
13 into which the cylinder is screwed and which
forms the bottom of the chamber A. The
5 bracket has a reduced screw-threaded nipple 14
screwed into the spark plug opening 15 of the
engine cylinder 16. A passage 17 leads through
the bracket and forms a communication between
the chamber A and the cylinder 16. The details
10 of the bracket and the various ways of mounting
the compressor will be hereinafter described.

A circular plate or disk 18 is secured in the
top of the chamber A by bolts 19 and immediately
below this plate the cylinder is provided with air
ports 20. The plate 18 forms a top for the cham-
ber A and a bottom for the chamber B. A sleeve
21 extends from the plate 18 axially into the
chamber B and has a flanged top or circular plate
22 at its upper end. A coiled spring 23 mounted
20 in the chamber B surrounds the sleeve and the
plate 22 and rests upon the plate 18.

A circular piston 24 provided with rings 25 has
a sliding fit in the cylinder 10, and a plunger 26
provided with rings 27 has a sliding fit in the
25 cylinder 11. These plungers are integrally con-
nected by a rod 28 which passes loosely through
the sleeve 21 and preferably out of contact there-
with. The coiled spring 23 supports the plunger
26 and normally holds the parts elevated.

To cushion the upward stroke of the piston I
provide a circular pad 29 on the under side of
the plate 18. This pad may be suitably secured
to the plate and may be made of rubber, rubber
compound, or any other cushioning material suit-
able for the purpose. On the plate 22, I secure
35 a similar pad 30, in any suitable manner. Upon
the up stroke the piston 24 will engage the pad
29 and cushion the piston, as well as prevent
the plunger 26 from striking the top of the cham-
ber B. Upon the down stroke of the piston the
plunger 26 will strike the pad 30 before the piston
strikes the bracket 12, thus cushioning this stroke.

In the top of the cylinder 11, I mount an inlet
valve cage 31 and an outlet valve cage 32. These
40 cages are screwed into the top of the cylinder so
as to be readily removed. The cage 31 has air
inlet ports 33 in its top and a valve seat 34 at its
bottom. A downwardly opening valve 35 engages
the seat and is provided with a stem 36 extending
45 through a spider 37 within the cage. The stem is
suspended on a coiled spring 38, whereby the
valve is normally closed. Upon the down stroke
of the plunger 26 the valve 35 will be opened and
air drawn into the chamber B, but upon the up-
50

55

ward stroke of the plunger said valve will be closed.

The cage 32 has a valve seat 36' at its bottom and an upwardly opening valve 37' engaging 5 therein. The valve has a stem 38' passing through a spider 39. The valve is normally held closed by a coiled spring 40 surrounding the stem between the valve and the spider. When the valve 35 is opened the valve 37' is closed and 10 when the valve 35 is forced closed the valve 37' is opened, whereby the air may be expelled from the chamber B. The cage 32 has a nipple 41 and a hose or other conductor 42 may be attached thereto.

15 The coiled spring 23 forms a very important part of this invention. Upon the down or intake stroke of the engine piston (not shown) in the cylinder 16, the piston 24 in the chamber A will be drawn downward and the spring 23 will be 20 compressed. When the engine piston starts on its upward or compression stroke, the compressed spring 23 will be free to expand and the energy thus stored up will be combined with the force exerted against the piston 24 in elevating 25 the plunger 26. The coiled spring 23 causes the engine piston to do more work or exert a greater force in pulling the piston 24 downwardly, therefore when the spring is released greater compression is built up in the chamber B. The 30 downward suction of the engine piston is exerted against the large piston 24 which has a large area, while the force of the expanding spring is exerted against the small piston 26, which has a small area. This causes the production of a 35 greater pressure in the chamber B. By this means both the intake stroke and the compression stroke of the engine piston are utilized and consequently a much higher pressure can be built up where the spring is used. In pumping up a 40 tire the resistance increases as the pressure in the tire increases and, therefore, the spring expedites the pumping operation and enables the tire to be inflated much quicker because of such spring.

45 While it would be possible to connect the bracket 12 at any convenient point on the engine cylinder 16, it is most convenient to connect it in the spark plug opening 15; but the invention is not to be so limited. The passage 17 of the 50 bracket is provided with an internally screw-threaded branch 43 and into this the usual spark plug 44 is screwed. By this arrangement the compressed charge will be ignited and all gases burnt in the usual manner. This will prevent 55 unburnt fuel from accumulating in the cylinder 16.

The passage 17 is also formed with a valve seat 45 opposite the spark plug for receiving a valve 46 suitably mounted on the end of a stem 60 47 having screw-threaded engagement in a box 48. The stem is provided with a hand wheel 49. When it is not desired to use the air compressor the valve 46 is closed against its seat 45, but this does not interfere with the operation of the spark 65 plug 44. Various forms of brackets or mountings may be utilized and the invention is not to be limited to the bracket shown or to the spark plug arrangement.

In using the device, it is mounted on top of 70 the cylinder 16 as is shown in Figure 1. Where it is not desired to use it in connection with a spark plug it can be otherwise connected to the cylinder. Upon the down stroke of the engine piston (not shown) and with the valve 46 open, 75 the suction created by such intake stroke will be

sufficient to pull the piston 24 downwardly, whereby the valve 35 will be opened and air drawn into the chamber B. As the pistons 24 and 27 move downwardly, the coil spring 23 will be compressed. The piston 27 will be cushioned at the 5 bottom of its stroke by the pad 30.

Upon the compression or upward stroke of the engine piston sufficient fluid will be forced through the passage 17 to elevate the pistons, and the compressed spring 23 being released will add 10 its energy to this upward stroke, thus making for a more powerful upward stroke. The valve 35 will remain closed, but after sufficient pressure is built up to overcome the tension of the spring 40 the valve 37' will be opened and the air expelled through the cage 32 and nipple 41 into the conductor 42. The pad 29 will cushion the 15 upward stroke of the pistons.

Various changes in the size and shape of the 20 different parts, as well as modifications and alterations, may be made within the scope of the appended claims.

Having illustrated and described a preferred 25 form of the invention, what I claim is:

1. In an air compressor for internal combustion 30 engines, an operating cylinder, a piston working in the operating cylinder, a compressing cylinder, a plunger working in said compressing cylinder, means for rigidly connecting the piston and the plunger, means for connecting the operating cylinder with the cylinder of a combustion engine, and means connected with the plunger for storing energy upon the intake stroke of the piston of the engine cylinder, said means co-acting with the compressor piston on the compression stroke of the piston of the engine to compress air in the compression cylinder. 35

2. In an air compressor for an internal combustion engine, an operating cylinder, a compression cylinder, a piston in the operating cylinder, a plunger in the compression cylinder, a rod connecting the piston and the plunger, a coiled spring in the compression cylinder supporting the plunger, an air inlet valve in the compression cylinder, an air outlet valve in the compression cylinder, and means connecting the operating cylinder with the cylinder of an internal combustion engine. 40

3. In an air compressor for an internal combustion engine, an operating cylinder, a compression cylinder, a piston in the operating cylinder, a plunger in the compression cylinder, a rod connecting the piston and the plunger, a coiled spring in the compression cylinder supporting the plunger, an air inlet valve in the compression cylinder, an air outlet valve in the compression cylinder, means connecting the operating cylinder with the cylinder of an internal combustion engine, a cushion member in the operating cylinder in the path of the piston, and a second cushion member in the compression cylinder in the path of the plunger. 50

4. In an air compressor, a support, an operating cylinder provided with air inlets mounted on said support, a plate secured within the upper end of the operating cylinder, a cushion mounted on the under side of the plate, a reduced compression cylinder extending from the operating cylinder above said plate, a sleeve carried by the 60 plate, a second cushion carried by the sleeve, a piston mounted in the operating cylinder, a plunger mounted in the compression cylinder, a rod connecting the piston and the plunger and extending loosely through the sleeve, an air ad- 65

mitting valve mounted at the upper end of the compression cylinder, an air outlet valve mounted at the upper end of the compression cylinder, and a coiled spring mounted within the compression cylinder and supporting the plunger.

5. In an air compressor for internal combustion engines, the combination with the operating cylinder of the air compressor, of a bracket having an upstanding annular flange in which the cylinder is secured, the bracket having a vertical passage extending therethrough and communicating with the cylinder, the bracket having a branch extending from said passage for receiving a spark plug so as to expose the electrodes thereof in said passage, the passage having a valve seat between the branch and the cylinder, a valve mounted in the bracket for engaging said valve seat for closing said passage,

and a screw-threaded shank mounted on the lower end of the bracket.

6. In an air compressor, a pair of cylinders one mounted above the other, air compressing elements working in said cylinders, an upright bracket supporting the cylinders in an upright position on top of an engine cylinder, said bracket having a passage therethrough leading to the bottom cylinder, a spark plug removably mounted in the side of the bracket and having its electrodes exposed in the passage thereof, a valve in the passage of the bracket between the spark plug and the cylinder having its stem extending through the other side of the bracket, and a nipple on the bracket below the spark plug for connection in the spark plug opening of an engine cylinder.

JAMES Y. TAYLOR.
